UNITED STATES PATENT OFFICE.

FRED E. ASELTINE, OF DAYTON, OHIO, ASSIGNOR TO GENERAL MOTORS RESEARCH CORPORATION, OF DAYTON, OHIO, A CORPORATION OF DELAWARE.

MIXING DEVICE.

Application filed July 2, 1923. Serial No. 648,892.

To all whom it may concern:

Be it known that I, FRED E. ASELTINE, a citizen of the United States of America, residing at Dayton, county of Montgomery, 5 and State of Ohio, have invented certain new and useful Improvements in Mixing Devices, of which the following is a full, clear, and exact description.

This invention relates to charge forming devices or fuel mixers for internal combustion engines using gaseous fuel such as natural gas or producer gas and the like.

Among the objects of the invention are:

To vary the fuel mixture proportions to suit the requirements of different fuels;

To obtain a rich mixture for engine starting when desired;

To prevent the escape of gaseous fuel from the mixer into the surrounding atmosphere;

To maintain the fuel proportions substantially constant during the operation of the engine over a wide range of variations in speed and in load;

To prevent over-charging the engine with fuel during idling by the accumulation of an over-rich mixture;

To control the mixture so that the engine may be readily started.

Further objects and advantages of the present invention will be apparent from the following description reference being had to the accompanying drawing wherein a preferred form of the present invention is clearly shown.

In the drawings:

Fig. 1 is a side elevation of the fuel mixer, portions being broken away to clearly illustrate certain elements of the device.

Fig. 2 is an end view of the device.

Fig. 3 is a plan view.

Fig. 4 is a detail sectional view of a portion of the air inlet passage showing the check valve.

Fig. 5 is a detail sectional view of the gaseous fuel passage including the valve and its operating element.

Fig. 6 is a detail view partly in section showing the adjusting element associated 50 with the air and gaseous fuel valves.

Referring to the drawings, the fuel mixer 20 is shown comprising a body portion 21, provided with a flange 22 by means of which the mixer is adapted to be secured to 55 an internal combustion engine not shown on

the drawing. 23 designates the mixing chamber which is in communication with air and gaseous fuel passages 24 and 25, formed by the hollow projections 26 and 27 respectively. These hollow projections are 60 shown as formed integral with the body portion 21 of the mixer 20. An air horn 28 is secured to the end of the projection 26 by means of screws 29, said air horn 28 being U-shaped and forming a curved continuation of the air passage 24. The outer end of the horn 28 has a Venturi tube 30 formed therein for the purpose of increasing the velocity of the air passing therethrough. The horn is provided to substantially 65 reduce the hissing noise generally present in carburetors and caused by air rushing through a restricted passage. The gaseous fuel passage 25 is adapted to be connected with any suitable source of gas- 70 eous fuel under pressure, which source is not shown in the present drawing.

The apparatus adapted to vary the fuel mixture proportions to suit the requirements of different fuels, comprises butterfly valves 80 31 and 32, positioned in the air and gaseous fuel passages respectively. The air controlling butterfly valve 31 is carried by a stem 33 journaled in the air horn 28. One end of this stem projects through the side of 85 said air horn and has the lever 34 secured thereto in any suitable manner. The gaseous fuel controlling butterfly valve 32 is mounted on a stem 35 which is journaled in the projection 27 forming the gas passage, one end of this stem 35 projecting to the outside of said passage and having the operating lever 36 secured thereto. A packing gland 37 surrounds the stem 35 to prevent gas leakage at this point, the packing 90 gland is held in stem engaging position by means of the packing nut 38. The lever 36 is provided with a spring pressed friction plunger 39 which is adapted to engage the radial track 40 secured to the outside of the body 21 adjacent to the lever 36, so that said lever will be maintained in adjusted position. The air and gas valve controlling levers 34 and 36 are connected together by means of an adjustable connection shown 100 in detail in Figs. 1 and 6. This adjustable connection comprises a screw threaded rod 41 having a right angle bent end 42 which is adapted to be secured to the lever 34 in any suitable manner. The opposite or screw 105 110

threaded end of the rod 41 slidably projects into the standard 43, rotatably supported on the lever 36 in any suitable manner.

Interposed between the levers 36 and 34 and screwed upon the rod 41 is an adjusting nut 44. The nut is held in engagement with the standard 43 by means of a spring 45, one end of which abuts against the nut 44, while the other end presses against the collar 46, held in position by means of a stop 47 provided on the rod 41. A sleeve 48, slidably arranged on the rod 41 between the nut 44 and the collar 46, prevents binding of the spring 45 on the screw threads of the rod 41. A tension spring 49 is also interposed between the two valve controlling levers 34 and 36 tending to draw the two together. The provision of the spring 49 in connection with the adjustable connection shown in Fig. 6 will hold these two levers in predetermined relation throughout the range of operation of both said levers. When it is desired to change the relative position of one valve to the other, the adjusting nut 44, which is normally held in adjusted position by means of the spring 45, may be rotated to either move the standard 43 toward or away from the angularly bent end of the stem 41, thereby tending to move the gas controlling valve lever 36 toward or away from the air controlling valve 34, thus changing the relative positions of the said valves to vary the fuel mixture proportions to suit the requirements of different fuels used with the mixer.

The means for obtaining a rich mixture for engine starting when desired, is included in the apparatus described above. As has been mentioned before the gas valve controlling lever 36 is provided with a friction plunger 39 which cooperates with the track 40 to hold said lever in adjusted position. The adjusting connection interposed between the two levers having a slideable connection between the rod 41 and the standard 43, mounted on the lever 36 will permit the lever 34, to which the rod 41 is anchored, to be moved away from the gas valve controlling lever 36 without causing the adjustment of the said lever 36 to be varied. The spring 49 will, when the air controlling valve lever 34 is released, cause said lever to be moved to the normal relative position and thus again restore the previous mixture proportions.

To prevent the escape of gas fuel from the fuel mixer into the surrounding atmosphere, or more specifically, from the mixing chamber 23 through the air passage 24, there is provided a check or flap valve 50 fulcrumed at a point 51 on an extension formed on the end of the air horn 28 which projects into the portion 26 of the housing 21. This valve is normally adapted to lie in a position as shown in Fig. 4 when com-

munication between the mixture chamber 23 and the air passage 24 is entirely cut off.

The means for maintaining the fuel proportions substantially constant during the operation of the engine over a wide range in speed and load, comprises a sleeve 55 slidably arranged in the mixing chamber 23 of the housing 21. This sleeve 55 is provided with a longitudinal slot 56 into which the end of the screw 57, screwed into and through the housing 21, is adapted to project. This prevents the sleeve 55 from rotating but will permit up and down movement thereof. Within the sleeve 55 there is positioned a lift plate 58 rotatably mounted on a pin 59, the ends of which project into and are supported by the sleeve 55. When in the position as shown in Fig. 1 this lift plate 58 is adapted to shut off the passage through the sleeve 55. The lift plate 58 is provided with an ear 60 to which the bifurcated end of the lever 61 is adapted to be secured by means of the pin 62. The opposite end of said lever 61 is fulcrumed on a pin 63 which is supported in a ring 64 fitting in the upper end of the passage in the housing 21. The lower end of the sliding sleeve 55 is provided with a cross pin 65 which supports the check valve 66. This check valve 66 has a tapered portion 67 which projects into and engages with the edges of the passage 68 when the sliding sleeve 55 is in its normal or low position as is shown in Fig. 1. The check valve 66 has a downwardly projecting portion 69 which may be termed the guide stem, said guide stem projecting through a spider 70 formed on the inside of the gaseous fuel passage 25. The check valve 66, will tend to prevent gaseous fuel from passing from the source of supply through the gaseous fuel passage 25 through the passage 68 into the fuel mixture chamber 23, when the sliding sleeve 55 is in the normal low position as is shown in Fig. 1.

The above apparatus including the sliding sleeve 55, the lift plate 58 and the check valve 66 also prevents flooding the engine during idling by the accumulation of an over-rich mixture.

The control of the mixture so that the engine may be readily started, is two phase, that is, for starting the engine when cold and for starting the engine after same has become heated. The means for controlling the mixture for starting a cold engine includes the manually adjustable air and gas controlling valves 31 and 32, the former being operable to restrict the air passing into the mixer without affecting the adjustment of the gas controlling valve, thus providing a rich mixture. For starting a warm engine, an over-rich mixture is practically unnecessary, thus the automatic proportioning of the mixture by the sliding sleeve 55,

the lift plate 58 and the check valve 66, brought into effect by the engine will facilitate the starting of the engine without manually altering the fuel mixture proportions.

5 The mixer operates in the following manner: When the engine is cold and it is desired to start the same, the operator moves the lever 36 in a clockwise direction about its support which will also operate the lever 34, due to the spring 49 being interposed between said levers, thus opening the valves 32 and 31, the former permitting gas to flow into the passage beneath the check valve 66, while the latter valve 31 will open the passageway 24 to permit air to be drawn therethrough. In order to facilitate the easy starting of the engine when cold, and after the preliminary adjustment of both the valve levers 36 and 34 has been completed, the operator may, in any suitable manner, operate the air controlling valve lever 34 in a counterclockwise direction without affecting or changing the adjusted position of the gas valve controlling lever 36, thus choking the air passage 24. Upon the cranking of the engine suction will be produced which will cause a subatmospheric condition in the passageway above the lift plate 58. This will tend to move said lift plate upwardly in the direction of the arrow shown in Fig. 1 and due to the fact that said lift plate is fulcrumed on the pin 59 secured to the slide sleeve 55, said slide sleeve will also be moved upwardly. The upward movement of the sleeve 55 will cause the lever 61, interposed between the stationary pin 63 and the rising lift plate 58 to rotate said lift plate 58 in a clockwise direction about its fulcrum pin 59, thus tending to open the passageway in the sleeve 55. The upward movement of said sleeve will also lift the check valve 66 from its valve seat associated with the passageway 68, due to the fact that said check valve 66 is secured to the sleeve 55 by means of the pin 65. The subatmospheric condition above the lift plate 58 will cause air to be sucked in through the air horn 28. The air thus passing through the passage 24 communicating with the air horn will lift the flap valve 50 and enter into the mixing chamber 23. The opening of the passageway 68 will permit the gas from the source of supply to flow through the passage 25, enter into the mixing chamber 23 where said gas will mix with the incoming air and be drawn into the intake manifold of the engine which communicates with the passage above the lift plate 58.

60 As soon as the engine becomes self-operative the operator releases the lever 34 thus permitting the spring 49 to move said lever to previous adjusted positions relative to the lever 36. Opening of the gas controlling valve 32 will increase the volume of gas

flowing past the check valve 66, while also increasing the volume of air flowing through the passage 24, thus increasing the volume of fuel mixture in the fuel mixing chamber 23, which when the engine is running below the maximum load for the given throttle opening, will flow into said engine and increase the speed, said increase in speed gradually tending to lift the lift plate 55 and thus opening the passageway in said sleeve to a greater degree and also opening the passageway 68 by the lifting of the check valve 66. However, when at any given throttle opening the load is increased, the speed of the engine will decrease, thus decreasing the suction above the lift plate 58, thus tending to cause the sliding sleeve 55 to drop and thus decrease the area of the passageway in said sleeve while also decreasing the aperture of the passageway 68 by the dropping of the check valve 66 with the sleeve 55. The inflowing air through the passageway 25 will also decrease due to the reduction in suction, thus it may be seen that the fuel proportions, that is, the proportions of the air and gas mixture will be maintained substantially constant during variations in engine speeds and loads.

When the engine is entirely at rest, suction above the lift plate 58 will be eliminated, thus causing the slide sleeve 55 with its check valve 66 to move to their normal down position, causing the check valve 66 to close the passageway 68 while at the same time the lift plate 58 will close the passageway through the slide valve 55. Thus it may be seen that even though the operator neglects to shut off the fuel supply which is under pressure, the fuel will be prevented substantially from entering into the intake manifold of the engine, thus tending to prevent flooding of the engine which would tend to make the starting thereof difficult.

The flap valve 50 will automatically shut off communication between the fuel mixture chamber 23 and the air intake passage 24 when the engine becomes inoperative. Thus if the operator neglects to shut off the gas supply by closing the gas controlling valve 32, any gas which might tend to leak past the check valve 66 and enter into the fuel mixing chamber 23 would be substantially prevented from entering into the air intake passage 24 and escape therethrough to atmosphere.

The numeral 90 designates a quick and efficient device for clamping the fuel mixer in position on an engine. This device includes elements 91 and 92 having semi-circular portions 93 and 94, said elements being held together by means of studs 95 and 96. The semi-circular portions 93 and 94 fit into a circumferential groove 97 formed in the body 21 of the fuel mixer directly beneath the flange 22. Two oppositely disposed

camming arms 98 and 99 are formed on the elements 91 and 92 respectively said camming elements having angularly arranged edges which are adapted to engage with a flange formed on the intake manifold of the engine and which when the clamping element is rotated in one direction, relative to the mixer and the intake manifold, will draw said fuel mixer into tight engagement with the manifold flange. The studs 100 are provided for the purpose of projecting into correspondingly arranged holes in the intake manifold flange, thereby to prevent relative rotation of the mixer with the manifold when the clamping element 90 is operated to draw the mixer into engagement with the manifold.

While the form of embodiment of the invention as described constitutes a preferred form, it is to be understood that other forms might be adopted all coming within the scope of the claims which follow.

What I claim is as follows:

1. A mixer for gaseous fuel and air comprising, in combination, separate passages for the admission of said fluids; separate valves controlling the respective passages; and means connecting said valves for producing movement of one valve by movement of the other, said means providing a rigid motion transmitting connection between said valves when one of said valves is moved in a certain direction, and providing a yieldable connection when said valve is moved in the opposite direction whereby both valves may be moved in concert or one independently of the other.

2. A mixer for gaseous fuel and air comprising, in combination, separate passages for the admission of said fluids; separate valves controlling the respective passages; levers each attached to a valve; a link pivotally attached to one lever and slidably connected with the other lever; a nut carried by the link for limiting the movement of one lever relative to the other; and a spring connecting said levers, whereby motion of one lever produces motion of the other lever and either lever may be moved independently of the other; the adjustment of said nut varying the relative position of one valve to the other.

3. A mixer for internal combustion engines comprising in combination, a suitable casing containing a mixing chamber, and air and gas passages leading thereto; a vertically movable hollow tubular sleeve fitting within said casing and guided within its movements thereby; an oscillation lift plate pivotally supported within said sleeve, and

partaking of the movements thereof; and a lever, the upper end of which is pivotally connected with said casing, and the lower end of which is pivotally connected with said lift plate to one side of the pivotal support aforesaid therefor.

4. A mixer for internal combustion engines comprising in combination, a suitable casing containing a mixing chamber, and air and gas passages leading thereto; a vertically movable hollow tubular sleeve fitting within said casing and guided in its movements thereby; an oscillating lift plate pivotally supported within said sleeve, and partaking of the movements thereof; a lever extended into said tubular sleeve and the upper end of which is pivotally connected with said casing and the lower end of which is operatively connected with said lift plate; and a valve carried by said tubular sleeve and cooperating with said gas passage to control the flow of gas into said mixing chamber.

5. A mixer for internal combustion engines comprising in combination, a suitable casing containing a mixing chamber, and air and gas passages leading thereto; a vertically movable hollow tubular sleeve fitting within said casing and guided in its movements thereby; an oscillating lift plate pivotally supported within said sleeve, and partaking of the movements thereof; a lever, the upper end of which is pivotally connected with said casing and the lower end of which is pivotally connected with said lift plate; manually operable valves for controlling the flow of air and of gas through said passages; and means connecting said valves to operate them in unison.

6. A mixer for internal combustion engines comprising in combination a suitable casing containing a mixing chamber and air and gas passages leading thereto; a vertically movable hollow tubular sleeve fitting within said casing and guided in its movement thereby; an oscillating lift plate pivotally supported within said sleeve and partaking of the movements thereof; and an operating member for said lift plate, the upper end of said member being held in a fixed position relative to said casing, and the lower end thereof being operatively connected with said lift plate to move the same about its pivotal support.

In testimony whereof I hereto affix my signature.

FRED E. ASELTINE.
